PINHOOK SETTING MACHINE FOR
DRAPERIES AND THE LIKEEdwin Raphael, Holland, Mich., assignor to Edwin
Raphael Company, Inc., Holland, Mich., a cor-
poration of Illinois

Application August 20, 1952, Serial No. 305,415

26 Claims. (Cl. 1—1)

1

The invention relates to machines for inserting pins or similar fastening devices in cloth fabrics and the like and, more particularly, is concerned with a machine whereby curtain or drapery pins or pin-hooks may be applied or inserted more or less automatically to or in a curtain, drapery or the like in a uniformly desirable manner and at a desired place. While the machine herein disclosed, or certain of its features, may be employed for other purposes, it is especially useful for the particular purpose of applying pin-hooks, i. e. combination pins and hooks by which curtains and drapes are hung, to curtains and drapes. Therefore, in the interest of simplification of description, the machine will be revealed in the form peculiarly adapted to that particular purpose.

Draperies, curtains and other hangings for interior decoration or for purely utilitarian purposes are hung or supported in various ways but commonly are hung upon rods, taut cables or the like. In some instances the drapery or other hanging may be mounted directly upon the supporting rod or other device as where a rod-pocket is provided in the hanging along a marginal portion thereof for reception of the rod support. More often, however, and especially for hangings of drapery and draw-curtains, the hangings are equipped with pin-hooks which include a pin shank portion to be inserted in or pinned to the material and a hook portion to be hooked over the supporting rod or hooked into eyelet or other devices in turn carried by the rod or support.

Much depends on correct placement of the pin-hooks for attainment of desired effects and correct appearance of the hanging. If the pin-hooks are of such type or construction that proper placement requires the pin shanks to be so placed in the material for instance, as to lie in parallel array, or to be arranged at equal intervals transversely of the hanging, or to be located at the same or some predetermined distance from the upper transverse marginal edge of the material or from a heading line, then any departure from such placement, array or location may cause the pin-hooks, supports or drapes or all to function improperly and, in any event, will be almost certain to destroy or prevent the desired effect or appearance. Therefore, it is of utmost importance that the pin-hooks be correctly pinned or set in the drapery or curtain and in the manufacture of such furnishings great care must be and is exercised with that end in view. Since the operation of inserting

2

or placing the pin-hooks has been performed manually heretofore and since so much care is required in performing that operation for reasons stated, a substantial part of the labor and expense involved in the manufacture of items such as curtains and drapes may be attributed to this phase of the manufacture.

One of the principal objects of this invention is to provide a machine by which pin-hooks or other pin devices may be placed speedily and with absolute precision in drapes, curtains and the like.

Another important object is to provide a machine of the character mentioned whereby drapes or the like and other fabric items, whether plaited, ruffled, folded or plain piece goods, may be pinned with pin-hooks or other pins or similar fastening devices for hanging or other purposes.

Still another important object is to provide a machine, of the type and for the purposes specified, capable of placing a pin-hook or a pin of other type in a pre-formed plait, seam or other part of a fabric item and at a predetermined place and in predetermined orientation therein with respect to the plait, seam or part and/or some other physical feature such as an edge of a heading or hem margin of the item, and, in connection therewith or independently thereof, to provide means for accommodating various thicknesses of materials and plaits, seams or folds.

A further object of a primary nature is to provide an arrangement of mechanism whereby a pin-hook or other pin may be so engaged with the fabric or other material that the final relative attitude of the pin shank and the plane or line of the material along the pin shank will be more or less parallel or, so that the material, between places engaged by the pin shank, may be straight and smooth, thereby to avoid "puckering" or "bunching" of the material along the pinned portion where puckering or bunching is undesirable. In this connection it should be mentioned that the machine embodies a work support and a pin inserting mechanism so constructed and related that a pin, point first, and the pin shank are caused to travel in a path, relative to that portion or part of the material in which the pin is to be secured, such as will intercept and enter the material at the desired point or place of entry, the pin point and shank being thereupon and thereafter caused to travel in a path whereby the pin point will lie or be disposed at a desired place or position wholly within a plait, seam or fold, or will

reenter or emerge from the material layer or layers at a desired point or place after the usual manner of a pinning operation heretofore performed by hand.

Still further objects include the provision of a work support of special utility and functions, a novel mechanism for guiding and inserting pin-hooks, a mechanism for securing material in a predetermined position while the pin-hooks are inserted, and magazine feed means for holding a plurality of "booked" or loose pin-hooks and supplying them successively as needed to the guiding and inserting or applying mechanism.

Many other objects as well as the advantages and uses of the invention will be appreciated and understood after reading the following description and claims and upon viewing the accompanying drawings in which:

Fig. 1 is a front elevation of a pin-hook setting machine primarily intended for setting pin-hooks in pinch plaits or other folds of draperies;

Fig. 2 is a view in side elevation of the right hand side of the machine shown in Fig. 1, illustrating in full lines the position of the pin-hook setting mechanism at the time of completion of insertion of a pin-hook, the dotted lines indicating the positions of certain of the parts of the setting mechanism in the normal inoperative position;

Fig. 3 is a side elevation of the left hand side of the machine with the parts illustrated in their normally inoperative position;

Fig. 4 is a top plan view of the machine;

Fig. 5-A is a fragmentary view partly in section taken along the section line 5-A-B—5-A-B of Fig. 4, illustrating the pin-hook setting head in its "down" or fabric clamping position and the pin-hook setting arm in engagement with a pin-hook in its initial position ready to start the pin-hook setting movement;

Fig. 5-B is a view corresponding to that of Fig. 5-A, taken along the same section line 5-A-B—5-A-B of Fig. 4, illustrating the pin-hook setting arm and pin-hook engaged thereby at the end of the setting arm stroke with the pin-hook engaged in the fabric in its final position;

Fig. 6 is the vertical section through the frame base portions, work support and a portion of the pin setter head, with parts broken away and omitted for sake of convenience, the section being taken substantially along section line 6—6 of Fig. 2;

Fig. 6-A is a transverse sectional view taken along the line 6-A—6-A of Fig. 1;

Fig. 7 is a horizontal sectional view taken substantially along the line 7—7 of Fig. 1 to illustrate the mechanism for lateral adjustment of the parts of the work support;

Fig. 8 is a sectional view through the pin-hook magazine taken substantially along the section line 8—8 in Fig. 1;

Fig. 8-A is a view of a standard type of drapery pin hook on a scale somewhat greater than the normal size, adapted for use in the instant machine;

Fig. 9 is a longitudinal section through the pin-hook magazine taken substantially along the section line 9—9 of Fig. 3;

Figs. 9-A and 9-B are transverse sectional views taken along respective line 9-A—9-B and 9-B—9-B of Fig. 9;

Fig. 10 is a perspective view of a drapery heading portion from the front side thereof showing one of the well known manners in which a French plait commonly is formed and held by permanent

stitching along the plait length or height and "tack" stitching;

Fig. 11 is a perspective view, from the rear side, of the drapery heading portion of Fig. 10 showing the plain seam formed by stitching the plait folds throughout their length across the drapery heading, and also showing a pin-hook in place as the same might be inserted by the machine disclosed herein;

Fig. 12 is a vertical section through the drapery heading at a plait, taken at the section line 12—12 of Fig. 11, the view showing the vertical stitching along the plait, the pin-hook in place and the thread of the "tack" stitches which hold the folds of the plait; and

Fig. 13 is a sectional view taken along the section line 13—13 of Fig. 12.

The drawings generally portray a machine built and successfully operated for application of pin-hooks to draperies and the like. In the construction of that machine it was deemed desirable to employ several different kinds of material (metal) for different parts and to an extent the section lining of the drawings hereof will reflect the kind or type of material employed in making that machine. Therefore, the section lining in the drawings, where departing from the usual simple type used to designate metal section, follows standards prescribed for different metals by American Standard Symbols for Section Lining as represented in a number of reference works including "Machinery's Hand Book," by Oberg and Jones, 14th ed. Copyright 1949, The Industrial Press, New York. Of course, choice of construction materials for the various parts of a machine of a character of the instant one is largely a matter for the discretion of the machine designer.

Construction

The machine frame includes a base portion 12 adapted to be mounted upon a bench 13 fragmentarily illustrated in Fig. 2 and to be held thereon by suitable bolts passing through drilled openings 14 extending through bosses 15 cast integral with the base and other parts of the frame. Rising from the sides of the base 12 and integral therewith are a pair of spaced flanges 16 which are drilled on aligned axes for the passage of a shaft 17 upon which a work support base or work-shoe holder 18 is secured as by a pin 19, the work support base 18 being drilled for passage of the shaft 17 therethrough. One end of the shaft 17, the left hand end viewing Fig. 1, is threaded as indicated at 21 for reception of a knurled clamp knob 22 which has a sleeve portion 23 the end of which is adapted to make frictional contact with the side of the adjacent flange 16 to lock the shaft 17 against rotation of oscillation relative to the machine frame.

At its opposite end, the shaft 17 projects outwardly beyond the adjacent flange 16 for reception of an elongated hub 24 of a worm gear 26 fixed on and to the shaft by a pin 25, the hub 24 being disposed so that one radial face normally bears against the exterior side of the adjacent flange 16. The worm gear 26 is housed within a gear case composed partly by an outwardly projecting circular part of a flange 27 integral with the adjacent flange 16 of the machine frame and a cover plate 28 secured to the first part by cap screws 29. The lower portions of the flange 27 provide spaced vertical walls which are drilled on aligned axes for reception of a shaft 31 rotatably mounted therein and carrying a worm 32 in meshing engagement with the worm gear 26. The worm 32 is secured to the shaft 31 for

rotation therewith and may have thrust engagement at its opposite ends with the adjacent interior walls of the depending parts of flange 27. A thrust collar 33 fixed on the rear end of the shaft 31 by a pin 34 permits the shaft 31 and worm 32 to rotate while retaining the shaft against displacement in one direction. A knurled knob 35 is secured to the shaft 31 for rotation of the shaft and may abut against the adjacent exterior side of the adjacent flange 27 to prevent rearward displacement of the shaft. When the knurled clamp knob 22 is unscrewed to release its inner end from frictional engagement with the side of the adjacent flange 16, rotation of the knob 35 will rotate the worm 32 whereby to rotate the worm gear 26 and the shaft 17. Since the shaft 17 is keyed to the work support 18, the latter will be swung forward or backward as the case may be, relative to and between the machine frame flanges 16.

The work support 18 rises above the upper ends of the base flanges 16 and at each side of a center portion is extended laterally and forwardly and rearwardly thereabove as indicated at 36 in Figs. 1, 2, 3 and 6. Extending laterally of the top surface of each of the upper portions 36 is a guideway, the bottom wall of which is designated 37 and the side walls of which are designated 38, while intermediate of the portions 36 is an upwardly extending projection 39. Each of a pair of complementary work support shoes 41-41', each the mirror image of the other, has an inverted T-shaped guide portion 42 adapted to seat and to slide transversely of the machine within the guideways 37-38 while gibs 43, which may be secured to the portion 36 by screws, serve to override the fore and rear edges of the guides 42 to prevent displacement of the work support shoes from the guideways.

Each work support shoe is drilled to provide a bore extending through it from side to side on aligned axes transverse to the machine and parallel to the guideways 37-38 and guides 42. Each drilled bore is tapped at its outer side as indicated at 44 for threaded mating engagement with threaded portions 45 of a shaft 46, one of the threaded portions 45 bearing a left hand thread and the other a right hand thread for a purpose to be described. The inner portions of the drilled bores may be counter-bored as indicated at 47 to provide clearance for the shaft 46 which also passes through and has bearing in a drilled bore in the projection 39. At each side of projection 39 shaft 46 is equipped with a thrust collar 48 for rotation therewith in abutting engagement with the opposite sides of projection 39. On one end of the shaft 46, a knurled knob 49 is secured so that the shaft may be rotated in either direction and since the threads of portions 45 are engaged with the correspondingly threaded portions 44 of the work support shoes 41-41', these shoes will either be moved toward or from one another transversely of the machine.

The upper surface 51 of each work support shoe 41-41' could be flat or of other contour but preferably is arcuately curved from front to rear, desirably being generated as a portion of a surface of a cylinder the axis of which is coincident with the axis of the shaft 17. The inner or adjacent edges of the work support shoes 41-41' project toward one another as indicated at 52-52', overhanging the center part of the shoe holder base member 18, and their upper surfaces 53-53' incline upwardly to their parallel terminal and adjacent margins from the surfaces 51-51'. The inclined surfaces 53-53' are arcuate in a fore and

rear direction concentric with the axis of the shaft 17 and surfaces 51-51'. The adjacent marginal edges of projecting portions 52-52' are rounded and their under sides may be tapered away from one another as indicated at 54-54' for a purpose which will later appear. The rear end or margin of each of the surfaces 51-51' terminates in a radially extending flange 55-55', the two flanges being aligned with one another and together serving as an abutment against which a fabric edge or margin may be abutted for gauging purposes. The upper portion of each of the frame flanges 16, the outer upper surface of flange 27 and the upper edge of cover plate 28 may be rounded as indicated at 56 to permit the work support shoes and base to swing freely forward and backward about the axis of shaft 17 and the forward upper portion of one of the flanges 16 may be provided with index markings 56 while the support base 18 may be provided with a fixed gauge marker 57 for registration with the index markings 56 thereby to determine the rotated position of abutment flanges 55-55' with respect to a vertical plane containing the axis of shaft 17 or with respect to the position at which the pin-hooks are to be placed.

Integral with the flanges 16 and base portion 12 and extending upwardly from the base portion at the rear thereof are a pair of parallel frame members 58 which at their upper ends extend forward to provide portions 59 overhanging the work support shoes and associated parts in spaced relation thereto. At their forward ends, portions 59 are integrally joined together throughout their vertical height as indicated at 61. Portion 61 is provided with a vertically extending T-shaped guideway 62 (see Fig. 6-A) formed in part by removable gibs 62' and within this guideway a correspondingly formed slide 63, integral with what will be termed the pin-setter head, generally designated 64, is mounted for vertical reciprocatory movements toward and from the work supporting shoes and work support. The upper end of the guideway 62 may be closed by a plate 65 secured to the frame portion 61 by cap screws 66.

The pin-setter head 64 comprises a pair of semi-circular housing members 67-67' each complementary to the other and held together as by screws 68'. Each of the two housing member halves has a semi-circular recess portion 68 mating with the corresponding recess in the other to provide a guide slot for reception of a pin-setter arm 69 carried by a lever arm 71 in turn secured to an oscillatable shaft 72 by means such as a pin 73, for swinging movements between predetermined limits about the axis of the shaft 72. Each of the housing members 67-67' has a pair of portions 74-74' projecting toward and substantially abutting against the corresponding projections on the other of these housing members, the inner side of projection 74 of each housing member being spaced from the adjacent inner side of projection 74' of such member to provide clearance for limited swinging of the lever arm 71 and to provide inclined surfaces 75-75' forming limit stops between which the lever arm 71 may be oscillated. The guide slot over a substantial length of the lower part of the pin-setter head is so dimensioned, transversely, as to receive and, together with the pin-setter arm 69, to guide a pin-hook during the insertion operation.

The pin-setter arm 69 is of arcuate shape to correspond to the curvature of the guide slot

provided by the registering recesses 68 between the housing parts 67—67' of the pin-setter head 64 and is dimensioned to have a sliding fit within the slot. At its free end arm 69 is cut away or reduced along its top and bottom edges 76—76' to conform generally to the hook portion H of a drapery pin-hook as clearly illustrated in Figs. 5-A and 5-B. Preferably the dimensions of the reduced end of the pin-hook setter arm 69 are such that it is not thicker, transversely, than the diameter of the wire of which the pin-hook is made and of a thickness between its top and bottom edges 76—76' somewhat less than the narrowest portion of the hook part H since, during the pin-setting operation, the hook part H is to be partly collapsed or sprung together as will be explained hereinafter.

The rear edge of each of the projections 73' is provided with half of a vertically extending slot which mates with the other half in the other projection for reception of a stem 78 of a fabric clamp, the lower or clamp portion of which is bifurcated as shown at 79 to provide a pair of toothed fabric clamping feet 81 disposed on opposite sides of the lower end portion of the housing members 67—67', the housing members at their lower ends being cut away as indicated at 82 for this purpose. The fabric clamp has a vertically elongated slot 83 through which the threaded stem of a clamp screw 84 passes for threaded engagement within a threaded bore in one or both of the projections 74'. By loosening and tightening the clamp screw 84 the fabric clamp may be adjusted vertically to a desired position on the pin-setter head with which it travels toward and from the work supporting shoes.

A boss 85 formed on the side of the upper portion of the right hand frame portion 59 carries a stub shaft 86 upon which a rocker arm 87 is pivotally mounted between the boss 85 and a nut 88 with a washer 89 interposed between the nut and rocker arm. The rocker arm 87 at its rear end is pivotally connected by a pivot bolt 91 to a link 92 adjustably connected with a connecting rod 93 which, at its lower end, is connected with a second yoke link 94 in turn pivotally connected, as at 95, with a foot operated lever 96 pivotally mounted on a pivot pin 97 between the sides of a bracket 98. The bracket 98 may be secured to the floor or upon any suitable pedestal in convenient location beneath the bench 13. A foot treadle 99 is provided on the other end of the lever 96 and a spring 101 connected between a forward end of the foot lever 96 and the bench 13, as by hook 102, normally holds the end of the foot lever in the upper full line position shown in Figs. 1 and 3 and dotted line position shown in Fig. 2. When the foot lever 96 is in its upper or inoperative position, the rocker arm 87 will be in the dotted line position shown in each of Figs. 2 and 3.

In the forward end of rocker arm 87 is an elongated slot 103 the long axis of which is in alignment with the pivot axes of the rocker arm on the stub shaft 86 and pivot bolt 91. Projecting from one end of a crank arm 104 is a pivot stud 105 which carries a roller sleeve 106 adapted to ride within and between the ends of the slot 103. The other end of the crank arm 104 is secured to the shaft 72 for oscillation of that shaft. The side of the frame adjacent to the crank arm 104 and rocker arm 87 has a vertically extending slot 107 of a length sufficient to permit the shaft 72 to move up and down to an extent

corresponding to vertical movement of the pin-setter head in the guideways 62.

Pin-hooks could be fed to the setter head and the setting arm 69 by hand but it is preferable that they be fed automatically from a magazine holding a substantial number for successive advancement to the setting mechanism. Accordingly, the machine illustrated is provided with a magazine feed mechanism adapted to hold a substantial number of pin-hooks and from which the pin-hooks may be fed automatically as required, one at a time and in proper oriented position, to the inserting mechanism. Preferably also, the magazine is of such type as will permit a plurality of pin-hooks to be assembled together in the same order or register in "booked" relationship as with lacquer, or the like, for insertion on an arbor in the magazine in such multiple unit form, yet also of such type as will permit the pin-hooks to be loaded individually without "booking." The magazine and pin-hook feed and the inserting mechanism desirably are of such construction and arrangement that the magazine may be removed with ease for reloading and replacement or for inner-change with a different magazine carrying a full charge of pin-hooks. Of course, with slight modification of the structure, pin-hooks of different sizes or different form might be utilized.

At a place adjacent to the upper or inoperative position (Fig. 5-A) of the reduced free end of the setter-arm 69, the housing member 67 has an opening 108 conforming generally to the overall profile outline of a pin-hook such as that shown in Fig. 8-A as that pin-hook may be viewed when in the position and with the orientation illustrated in Fig. 5-A. The opening 108 extends from the exterior of the housing member 67 to the guide slot provided by the recesses 68 thereby to permit the pin-hooks to pass from the magazine into the guide slot and on to the end of the pin-setter arm as shown in Fig. 5-A. A U-shaped or channel member 109 is provided with lateral flanges 111 at one end thereof for abutment against the exterior surface of housing member 67 along opposite margins of that housing member defining the opening 108, cap screws 112, passing through those flanges into the housing wall to secure the member 109 in its position where it projects laterally from the side of the machine. Disposed in the bottom of channel member 109 and relatively permanently secured therein as by screws 113, is a lower pin-hook guide member 114 which is formed with a groove 115 extending throughout its length, the groove being transversely contoured as indicated in the section of Fig. 8 thereby to conform generally to the lower part of the outline of a pin-hook when oriented as above stated. Fitting on top of and mating with the lower guide 114 within the channel 109 is an upper pin-hook guide member 116 formed with a groove 117 conforming in transverse contour to the upper part of the outline of a pin-hook oriented in the manner previously stated.

The upper guide 116 also has a longitudinally extending groove 118 adapted snugly but removably to receive a pin-hook arbor 119 which fits therein throughout its length, and is secured therein by screws 119', and has a projecting tongue portion 121 which is received in the opening 108 for centering and aligning purposes. Pin-hooks in multiple number, whether "booked" or separate, are slidably threaded on to the arbor and are fed forward therealong into the opening 108 and on to the end of the setter-arm 69 by

a follower 122 carried on a guide rod 123 and slidable therealong within the confines of the upper and lower pin-hook guide members 114, 116, the follower having a configuration permitting it freely to slide longitudinally in the grooves of the upper and lower guide members and about the pin arbor 119. A spring 124, surrounds the rod 123 and reacts between a fixed abutment 125 on the outer end of the rod and the follower 122, normally urging the follower toward a limiting abutment or stop 126 at the inner end of the rod. The lower end portion 120 of the arbor 119 is forked to straddle the rod 123 and spring 124. The outer end of the rod 123 has a return bent portion 126' the free end of which is provided with a hook part 127 adapted to pass into a drilled bore 128 extending through the U-shaped housing member 109 into the lower pin-hook guide member 114. A pair of handles 129 secured to the upper pin-hook guide 116 may be employed for the removal of the upper pin-hook guide member 116 and the pin-hook arbor 119 after the rod 123, spring 124 and follower 122 have been removed as an assembly, the rod end 127 being first removed from the bore 128. A pin 130 (Fig. 4) secured to and projecting from the upper pin-hook guide member 116 rides in a slot 131 provided in the outer end of the channel member 109 and requires the upper pin hook guide member 116 to be removed or slid longitudinally to the left viewing Figs. 1, 4 and 9 for removal of the tongue 121 from the opening 108 before being lifted out of the channel member 109.

Operation

In describing the operation it will simplify matters to refer to one manner in which the machine may be employed to apply or insert pin-hooks in interior hangings such as drapes. It will be assumed that the drape is composed of cloth fabric, as shown more particularly in Figs. 10 to 13, inclusive, and has a cloth fabric lining on the reverse side, that it is to have a "heading" 131 extending to a predetermined height above the line of support, that "pinch" or multi-fold plaits extend across the heading in transversely spaced relation to one another, that pin-hooks are to be placed or inserted in the fabric material on the reverse side thereof at each fold or plait and at exactly the same distance from the top margin or top edge of the "heading," that the pin shanks or hooks or both are to be arrayed in parallelism and perpendicular to the top margin of the "heading," and that the pin points as well as the shanks are to be concealed within the material or the drape folds so that neither of such pin-hook parts will "grin through" at either side of the drape.

As is well known and well established practice in the industry, drapery plaits of the type illustrated herein may consist of several pinch folds of which three, 132, 133, 134, are shown in Fig. 6 and in Figs. 10, 11 and 13, wherein the cloth material is shown as doubled back upon itself to provide four folds 135, 136, 137 and 138, and secured in such folded condition. The heading 131 may be tacked down by sewing 139. The usual and ordinary method of securing the folds of the illustrated plait is by sewing the two outermost folds 135 and 138 directly together by sewing down the valleys of the folds, as shown at 140, over their length or height across the heading 131 and thereafter "tack" sewing the three pinch folds 132, 133 and 134 at the bottom of the heading, as indicated at 141, the "tacking" being done at the lower ends of the folds or plaits and usually within the

drapery heading area or close thereto. These plait forms and sewing thereof are old and well known practices as shown and described, for instance on pages 119, 120 of "The New Encyclopedia of Modern Sewing," Wm. H. Wise & Co., Inc., N. Y., 1946, copyright 1943 by The National Needlecraft Bureau, Inc., revised edition, copyright 1946, Wm. H. Wise & Co., Inc. See also page 268 of "The Complete Book of Sewing," by 10 Constance Talbot, Garden City Publishing Co., Inc., Garden City, New York, copyright 1943 by Book Presentations, New York, and page 140 of "The Wise Encyclopedia of Modern Sewing," Wm. H. Wise & Co., Inc., New York, 1950, copyright 15 1947, 1948, 1949, 1950 by Wm. H. Wise & Co., Inc.

The machine parts being in their normal inoperative positions as shown in full lines in Fig. 3 and in dotted lines in Fig. 2, the first preliminary operation may be the forward or rearward adjustment of the work support and work supporting shoes 41, 41' to set the work margin abutment flanges 55 at such predetermined distance from some fixed or datum point circumferentially about the axis of shaft 17, as will result in placement of some particular point on or part of a pinhook at that distance from the top marginal edge of the drape "heading" as will give the drape its support at the desired line. The scale markings 56 and index plate 57 may be graduated and arranged to determine the desired position of the work stops 55. Upon release of the clamp knob 22 the adjustment knob 35 may be rotated in one direction or the other to turn the shaft 17 through operation of the worm 32 and worm gear 26 thereby to swing the support base 18 and the work support shoes 41, 41' forward or backward until the index plate 57 registers with the desired mark on scale 56. Thereafter the clamp knob 22 is again tightened to secure the setting.

40 The next step may be the adjustment of the slot width between shoes 41, 41'. If the drapery plaits are all of the same general type and transverse thickness, only one transverse setting of the shoes may be required to provide the correct 45 slot width for disposition of all of such plaits therein so that it is not necessary to readjust the slot width until a thicker or thinner plait is to be pinned. Adjustment of the slot width is readily accomplished by rotation of the knurled knob 50 49 which, through the oppositely threaded portions of shaft 46, simultaneously moves both work support shoes 41, 41' toward or from one another along guideways 37-38. The slot width preferably is such as to furnish a firm but light pressure 55 on the material at opposite sides of the plait but the lips of the projections 52, 52' should not be so close together as to interfere with the insertion or placement of the pin point and shank of a pinhook.

60 Grasped by hand along a portion of the upper part of the plaited drape with the rear, or reverse side of the drape upward, the upper edge is thrust over the surfaces of the work support shoes 41, 41' with the plait to be pinned depending into the slot and with the material at each side of the plait disposed downwardly and outwardly over the inclined upper surfaces 53, 53' and the cylindrical surfaces 51, 51' of the work shoes after the manner illustrated in Fig. 6. The upper edge of the drape is brought up evenly against the adjacent faces of the work stops 55.

With the work so placed on the work support the operator depresses the foot treadle which, 75 during the first part of its movement, permits the

11

setter head to lower by action of gravity until the work clamp feet 81 make firm clamping engagement with the work, the feet 81 pressing the work against the sloping or inclined surfaces 52, 52'. The depression of treadle 99 urges the connecting rod upward thereby swinging rocker arm 87 in a counterclockwise direction, viewing Fig. 2 from the dotted line position shown in that figure toward the full line position. As the rocker arm starts this swing carrying the crank 104 with it, the shaft 72, being attached to crank 104, drops down the slot 107 and the entire setting head 64 carrying the fabric clamp 79 drops with it. The slot 103, of course, permits freedom of movement of the crank arm within limits with respect to the rocker arm since the rocker and crank arms have different swinging radii and other differential movements. During the first part of the depression of treadle 99 then, the fabric is clamped to the work support but there has been little if any rotative movement of the shaft 72, lever arm 71 and pin-setter arm 69 as Fig. 5-A indicates. However, at this time a pin-hook will have entered the slot and been disposed as shown over the reduced end of setter arm.

It will be helpful to an understanding of certain functions performed by the setting mechanism, to digress momentarily from the statement of operation to describe the type of pin-hook employed with the machine of the instant embodiment. The pin portion of this pin-hook normally is closed against the hook portion as shown in Figs. 5-A and 8-A. As most clearly illustrated in the latter figure, the hook portion H is a loop somewhat of horse-shoe shape since the loop ends are curved in toward one another while the shank part S of the pin portion is bent back rather sharply at one side of the hook loop so that it is substantially tangent to the outer side of the loop of the hook portion, as indicated at C. Whether the shank portion actually makes contact with the loop of the hook portion or merely extends in close proximity thereto generally is not of material consequence so long as the gap between these portions at C is sufficiently narrow and the pin-hook wire has a degree of resilience or spring quality sufficient to offer resistance to the escape of the fabric from within the small loop between such portions. The shank portion terminates in the usual point P. The opposite or free end of the hook portion H terminates in an outwardly flared nib F which is designed primarily to facilitate engagement of the hook over drapery supports such as rods and by reason of this flared part the pin-hook has greater transverse width at this place than the transverse width at any other section. Advantage is taken of this last mentioned feature of the pin-hook to aid in opening a gap between the pin shank portion S and the hook portion H at point of tangency C to permit easy entry of the pinned material therebetween into the small loop, the natural resilience of the pin-hook wire being relied upon again to close the pin shank portion against or toward the hook portion upon passage of the pinned material past the gap into the small gathering loop.

As will be seen upon inspection of Figs. 5-A and 5-B, the opposed and abutting projections 74' of the housing members are cut away at the juncture of the radially angular edges 75' with their arcuate walls 70, as indicated at 70', to permit the nib F free entry into the pin-hook guide slot 68 over the end of setter arm 69. However, since the radial width of the remainder of the guide slot between the arcuate wall 70 and 75'

12

the opposed outer wall of such slot is less than the transverse width of the pin-hook thereacross at the nib F, movement of the pin-hook into such narrower part of the slot under impetus of the setter arm 69 will cramp the pin-hook transversely causing the nib F to be moved resiliently toward the opposite side of hook portion H. It will also be noted in these Figs. 5-A and 5-B that the housing members 67, 67' terminate in a plane parallel to a tangent or substantially parallel to a tangent to the upper edge of the arcuate lips of the work support projections 52, 52' substantially at the mean of the pin shank length so that, when the setter head is in its "down" position, as shown, the terminal surface 88 becomes substantially tangent to the arcuate edges of the work support lips and the pin-hook guide slot is opened on its outer side for emergence of the pin shank portion S including point P. Therefore, as the treadle 99 is further depressed beyond the point above mentioned, the radial lever arm 71 swings in a clockwise direction (Figs. 5-A and 5-B) from the position in Fig. 5-A to that in Fig. 5-B, causing the setter arm 69 to move the pin-hook with which it is engaged into and along the confining part of the guide slot with the nib F compressed toward the opposite side of hook portion H. When the pin-hook reaches that portion of the guide slot which is open at the outer side thereof the pin point P followed by the succeeding increments of the shank portion S will spring or tend to spring radially outward away from the adjacent parts of the hook portion H thereby "opening" the pin to provide a gap at C to permit passage of the material therethrough into the gathering loop at the junction of the shank portion S with the hook portion H. The emerging point of the pin-hook will be inclined downward toward the material with which it is to engage and into which it is to be inserted but will continue to be swung in an arc. The result is that the pin point and the balance of the pin shank will enter the material or the seam of the fold or plait and come to rest (upon completion of movement of the setter arm 69) in the position illustrated in Fig. 5-B and Fig. 6.

Upon release of the treadle 99, the spring 101 will return all of the operating parts of the machine to their initial inoperative positions the inserted, pin-hook, of course, remaining where placed in the material. As soon as the setter arm returns to the position shown in Fig. 5-A the magazine mechanism operates to place the next pin-hook over the receiving end of the setter arm which, until such position is attained serves to obstruct the entry of pin-hooks into the guide slot. With the return of the setter head to its uppermost or inoperative position, as in Fig. 3, the fabric clamp is raised away from the material to permit the drape or other work to be removed.

The invention has been described and illustrated in a presently preferred form for a particular purpose but, as will be appreciated, it is susceptible of embodiment in other forms and for other purposes and many variations in construction and arrangement may be made. Consequently, I desire to be limited only by the invention spirit and the scope of the appended claims.

I claim:

1. A machine for setting pin-hooks comprising, means for supporting fabric having a pre-formed fixed plait with the plait in a predetermined po-

13

sition, and means for inserting a pin-hook in the fabric at the plait with the pin shank of the pin-hook extending substantially longitudinally with respect to the plait of the fabric and the hook in predetermined relation to the shank.

2. A machine for setting pin-hooks comprising, means for supporting fabric having a pre-formed fixed plait, said supporting means providing an elongated slot for reception of the plait with the plait fold lines extending longitudinally of the slot and means for inserting a pin-hook in the fabric longitudinally of the plait folds and in predetermined position with respect to the said fold lines of the plait of the fabric.

3. A machine for setting pin-hooks comprising, means providing a support for a piece of fabric having a pre-formed fixed plait therein extending substantially perpendicular to an edge thereof, means associated with said support means for positioning said edge of the fabric with said plait in a predetermined oriented position, and means for securing a pin-hook in said fabric in predetermined relation to the oriented position of the fabric edge and the fabric plait.

4. A machine for setting pin-hooks comprising, means providing an upwardly facing supporting surface for a piece of fabric having a pre-formed fixed plait therein, said means having a slot into which said plait may depend, means associated with said means for positioning an edge portion of the fabric in a predetermined oriented position, and means for securing a pin-hook in said fabric in predetermined relation to the oriented position of the said fabric edge and the said plait.

5. A machine for setting pin-hooks comprising, means for supporting and securing a piece of material having a pre-formed fixed plait therein with a portion of the plait in a predetermined spaced position and orientation with respect to a predetermined edge of the material, and means operable to secure a pin-hook in said portion with the hook in predetermined spaced position and orientation relative to said material edge.

6. A machine for setting pin-hooks comprising, a work support including an arcuately convex surface portion upon which material such as a piece of fabric conformably may be placed for operation thereon, a pin-hook holder, and means associated with said holder and engageable with the hook part of a pin-hook held by the holder for inserting the pin-hook in the material with the shank of the pin extending in a path substantially parallel to a chord of an arc of said convex surface.

7. A machine for setting pin-hooks comprising, a work support including an arcuately convex surface portion upon which material such as a piece of fabric having a plait therein conformably may be placed for operation thereon, said work support having a downwardly extending slot for reception of the plait, a pin holder, and means associated with said holder and engageable with a pin held thereby for inserting the pin in the material parallel to the fold axis of the plait with the shank of the pin extending in a path substantially parallel to a chord of an arc of said convex surface.

8. A machine for setting pin-hooks comprising, a work support including a convex work receiving surface portion upon and over which at least a part of a piece of material such as fabric conformably may lie for operation thereon, a pin-hook holder and guide associated with said work support, and means including said guide for mov-

14

ing a pin-hook in a path substantially tangential to the convexly lying part of the material and inserting the pin-hook in the material with its shank portion extending substantially parallel to a chord of said surface portion convexity and the hook portion in predetermined orientation to a predetermined part of the material.

9. A machine for setting pin-hooks comprising, a work support including a convex work receiving surface portion upon and over which at least a part of a piece of material such as fabric having a plait therein conformably may lie for operation thereon, said work support having a downwardly extending slot for reception of said plait, a pin guide associated with said work support, and means including said guide for moving a pin in a path substantially tangential to the convexly lying part of the material and inserting the pin in the material at the plait with its shank portion extending substantially parallel to a chord of said surface portion convexity.

10. A machine for setting pin-hooks comprising, a work support having a surface adapted to receive and position a piece of material such as fabric with a physical feature of the material in predetermined position relative to such surface and with that part of the material that is to receive a pin-hook exposed, means for clamping the work in said position upon the support, means for holding a pin-hook to be inserted in said material, and means operable to engage said pin-hook and to move the same in an arcuate path parallel to a tangent to the exposed surface of that part of the material into which the pin-hook is to be inserted, said path being so located with reference to the said material that the pin-hook point will enter the material at a place having predetermined spaced and oriented relation to said physical feature.

11. A machine for setting pin-hooks comprising, a relatively stationary work support having a surface adapted to receive and support a piece of material such as fabric having a fold adjacent to an edge thereof, a work stop carried by said support for engagement with said material edge to position said edge, means for holding a pin-hook to be inserted in said material in predetermined relation to the line of said fold, and means operable to engage said pin-hook and to move the same in an arcuate path parallel to a tangent to the exposed surface of that part of the material into which the pin-hook is to be inserted, said path being so located with reference to the said material that the pin point will intercept and enter the material at a place having said predetermined relation to said fold.

12. A machine for setting pin-hooks comprising, a relatively stationary work support having an upwardly facing surface adapted to receive and support a piece of material such as fabric having a fold extending in a direction transverse to an edge thereof, a work stop for engaging said material edge to position said edge and fold in one direction parallel to said surface, means for positioning said fold in a predetermined position in a direction normal to said one direction and parallel to said surface, means for holding a pin-hook to be inserted in said material, and means operable to engage said pin-hook and to move the same in an arcuate path parallel to a tangent to the exposed surface of that part of the material into which the pin-hook is to be inserted, said path being so located with reference to the said material that the pin point will enter the ma-

terial at a place having predetermined relation to said fold and said edge.

13. A machine for setting pin-hooks comprising, a work support having an upwardly facing surface to receive and support a piece of material such as fabric, means for positioning the material by an edge portion thereof in a predetermined position, means for holding a pin-hook to be inserted in said material, and means operable to engage said pin-hook and to move the same in a path intercepting the exposed surface of that part of the material into which the pin-hook is to be inserted, said path being so located with reference to the said material that the pin point will enter the material at a place having predetermined relation to said edge portion.

14. In a machine of the character and for the purpose described, a work support having a variable slot therein and a raised lip along each side of the slot for supporting a piece of material with a predetermined portion thereof in raised elevation relative to adjacent portions, means for clamping the material against the raised lips, and means for engaging and moving a pin with its point foremost in a path intercepting said raised portion of the material and effecting insertion of the pin therein.

15. In a machine of the character and for the purpose described, a work support for supporting a piece of material with a predetermined portion thereof in raised elevation relative to adjacent portions, means for moving said support, positioning means carried by said support and movable therewith for said predetermined portion, and means for engaging and moving a pin with its point foremost in a path intercepting said raised portion and effecting insertion of the pin therein with the pin shank axis in predetermined orientation in said portion.

16. A machine for setting pin-hooks comprising, means for supporting a piece of flexible material with a predetermined portion thereof convexly arched, means for positioning said portion in a predetermined orientation on said support, and means operative to insert the shank part of a pin-hook in said portion with the pin shank part disposed along a chord of the arch of the said portion in said predetermined position.

17. In a machine of the character and for the purpose described, a work support including two parts movable relatively toward and from one another and between them defining a variable width slot for reception of a portion of the work, means for holding a pin to be inserted in the work at the position of said slot, and means operative to engage a pin and to insert the same in the work between the sides of the slot.

18. In a machine of the character and for the purpose described, a work support including two parts movable relatively toward and from one another and between them defining a variable width slot for reception of a downwardly projecting portion of the work, means for holding a pin to be inserted in the work at the position of said slot, and means operative in a path extending in a direction which is longitudinal of said slot to engage a pin and to insert the same in the work at the location of said downwardly projecting portion between the sides of the slot.

19. In a machine of the character and for the purpose described, a work support for a piece of fabric having a terminal edge and a plait the line of which extends transversely of the line of such edge, said support including two parts movable relatively toward and from one another and

between them defining a variable width slot for reception of said plait in depending position, guide means associated with said support for limiting engagement with said fabric terminal edge, means for holding a pin-hook to be inserted in the said plait at the position of said slot, and means operative to engage the pin-hook and to insert the same in the plait between the sides of the slot in predetermined spaced relation to said guide means.

20. In a machine of the character and for the purpose described, a work support including a pair of members, each of said members having an upwardly convex arcuate surface, said arcuate surfaces being substantially parallel in side by side relation, means for moving said members toward and from one another along an axis of generation substantially common to each of said arcuate surfaces, and means disposed above said surfaces and cooperative therewith for performing work on material disposed on said surfaces.

21. In a machine of the character and for the purpose described, a work support including a pair of members, each of said members having an upwardly convex arcuate surface, said arcuate surfaces having a substantially common axis of generation and being substantially parallel in side by side relation, means disposed above said surfaces and cooperative therewith for performing work on material disposed on said surfaces, means for moving said members relative to one another and to said work performing means in a path substantially parallel to said common axis of generation of said surfaces, guide means providing a work edge-engaging surface for limiting movement of work across said surfaces in a direction transverse to said axis of generation, and means for varying the position of said guide means relative to said work performing means.

22. A machine for inserting pin-hooks in draperies and like fabric items for hanging purposes comprising, a work support including an upwardly facing surface for reception of that portion of the fabric item into which the pin-hook is to be inserted, means cooperative with said support for securing the fabric item portion in a relatively fixed position on said surface, means for holding a pin-hook, and means operable to receive the pin-hook from said holding means and to insert the pin-hook shank, point first, into said item portion.

23. A machine for inserting pin-hooks in plaited draperies and like fabric items for hanging purposes comprising, a pair of adjacent work supporting members each having an upwardly facing convexly arcuate surface for reception of portions of the fabric item adjacent to a plait portion into which the pin-hook is to be inserted, the said surfaces being substantially parallel in side-by-side relationship, means for moving said members toward and from one another in said parallel relationship to provide a variable width slot between said surfaces for reception of the plait portion into which a pin-hook is to be inserted, means cooperative with said supporting members for securing the fabric item portions in relatively fixed and predetermined positions on said surface and within said slot, means for holding a pin-hook, and means operable to receive the pin-hook from said holding means and to insert the pin-hook shank, point first, into said item plait portion.

24. A machine for inserting pin-hooks in plaited draperies and like fabric items for hanging purposes comprising, a work support including an

upwardly facing surface for reception of that portion of the fabric item into which the pin-hook is to be inserted, means for positioning a predetermined part of a fabric item on said surface in predetermined relationship to a plait therein and to an edge thereof, means cooperative with said support for securing the said fabric item part on said surface as positioned by said positioning means, means for holding a pin-hook, and means operable to receive the pin-hook from said holding means and to insert the pin-hook from shank, point first, into the fabric item in a position having predetermined relation to said secured part.

25. A machine for inserting pin-hooks in draperies and like fabric items for hanging purposes comprising, a work support including an upwardly facing surface for reception of that portion of the fabric item into which the pin-hook is to be inserted, means cooperative with said support for securing the fabric item portion in a relatively fixed position on said surface, magazine means for holding a plurality of pin-hooks, and means operable to receive the pin-hooks successively from said magazine and to insert a pin-
hook shank, point first, into said item portion.

26. In a machine for setting pin-hooks in

draperies and the like, wherein each pin-hook has a pointed-end shank portion and a reversely bent section providing a hook portion opening in a direction substantially opposite to the point of the pointed-end and the shank and hook portions are substantially tangent to one another between the limits of the shank length, means for supporting a drapery in a predetermined position for insertion of a pin-hook in a predetermined place thereof, and means for inserting a pin-hook in said place, said means being effective to spread said shank and hook portions relatively apart.
